Primary Examiner — Cynthia Ramirez(74) *Attorney, Agent, or Firm* — James L. Young;
Westman, Champlin & Koehler, P.A.(57) **CLAIM**

The ornamental design for a shopping cart component, as
shown and described.

DESCRIPTION

FIG. 1 is an isometric view of a shopping cart component
assembly;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the figures are included for the
purpose of illustrating environment and forms no part of the
claimed design.

1 Claim, 7 Drawing Sheets(56)
